LOCOMOTIVE STOKING MECHANISM

David T. Williams, New York, N. Y., assignor to
the Standard Stoker Company, Incorporated, a
Corporation of Delaware

Application September 21, 1927
Serial No. 220,964

9 Claims. (Cl. 110—101.)

The object of this invention, which relates to automatic stokers, particularly for locomotives, is to improve the means for delivering the fuel to and distributing it over the fuel-bed so that the placement of the fuel at any or all points on the fuel bed may be readily accomplished under the control of the fireman; that the mechanism may be applied to any existing locomotive with the least possible interference with existing structure and so as not to encumber otherwise useful space; that it may be adapted, whenever automatic feeding-forward of the fuel from the bunker to the point for delivery into the fire-box fails for any reason, to lend itself to hand-firing subject to the above-indicated selective placement of the fuel on the fuel-bed under the control of the fireman and also adapted to be quickly and easily removed as an entirety if for any reason such becomes necessary or desired; and that it may be further adapted when the firing is being done manually for operation in part by man-controlled mechanically operated means, as that now commonly used for moving the closure for the firing opening of the furnace.

Fig. 1 shows the improved mechanism in side elevation in position on a locomotive of which the rear portion appears in vertical section;

Fig. 2 is a rear elevation of what appears in Fig. 1, but partly in section;

Fig. 3 is a horizontal section on line 3—3, Fig. 1, in which a certain box partly appears in such section and the top of the conduit terminal and certain other parts appear in plan;

Fig. 4 is a vertical section on line 4—4, Fig. 1; and

Fig. 5 is a vertical sectional view of a detail. 1 is the upwardly directed elbow of a conduit 2 through which, by means of a screw 3 in the conduit rotated from a steam-engine 4, the fuel (coal) is forced forward from the bunker of the tender and to the top of such elbow. The elbow in the present example protrudes somewhat above the floor 5 of the locomotive cab, back of the rear wall of the fire-box of the furnace, whose firing opening is shown at 6 and its grate-level at x, it being understood that the level of the fuel on the grate does not exceed approximately the level of the bottom of the opening 6. It is now common practice to provide the firing opening with closure means which is normally closed and fluid-operated for opening subject to the control of the fireman, as by pressure on a pedal, so that cold air is excluded from the firebox except when he is actually entering each shovelful

of coal and he is relieved from hand-manipulation of the closure means. Such a mechanism is generally shown in the drawings as comprising guides 7 at both sides of the opening 6; closure means therein, usually consisting of a pair of doors which slide to and from each other in the guides but here is shown as comprising a single door 8 normally held closed; fluid-actuated means 9 for effecting the opening of such door having a lever 9a fulcrumed at 9b connected on the one hand with a stud 9c of the piston of such means and on the other with a stud 9d on the door 8; and a pedal 10 for operating the valve controlling the fluid for actuating the means 9; as this mechanism forms no part of my invention a more particular description thereof is unnecessary.

The elbow 1 projects up back of the firing opening 6 and has a frontal discharge opening thereto but is otherwise closed at the top (normally) and at all sides. To this end the terminal 1a of the elbow 1 is preferably surmounted by the following structure: 11 11 are two side walls and 12 a rear wall bolted together in rectangular arrangement; 13 being a top wall or cover pivoted, on a horizontal bolt 14, to the two side walls near the firing opening 6, the whole thus forming a housing or box open to receive the fuel elevated thereto from the terminal and also at the front, where the mentioned discharge opening, designated 1b, exists, and closed at the back and two sides and also (normally) at the top. It is removably attached to the terminal by bolts 15 pivoted to the sides of the latter and received by notches 11a in the basal flanges 11b of the side walls 11 and having clamping nuts 15a to bear on such flanges.

The back wall 12 forms a fluid manifold, having a main chamber 16 extending its full length and forward thereof a line of distributing chambers 17 each of which is provided with a horizontal line of jet-outlets 17a open toward discharge opening 1b and has a valve-seat 17b affording communication with the main chamber through the partition 12a separating the latter from the distributing chambers. Screw-valves 18 arranged to seat on the valve-seats 17b with their handles 18a projecting rearwardly are mounted in the manifold, so that the supply of fluid from the main to any distributing chamber can be cut off or varied. The supply to the main chamber is afforded by a pipe 19, which may take fluid from any fluid source, as the locomotive boiler. The manifold affords means whereby, as fast as

the fuel mass is elevated in the terminal, it may be projected through discharge opening 1b and hence through the firing opening 6 into the firebox: since the jets are alined the blast possible to be attained will exist substantially as a sheet.

Distribution of the fuel to any part or all parts of the fuel-bed is accomplished as follows: On a horizontal axis extending across the firing opening 6 and arranged in the front upper part of the terminal 1a are pivoted to move up and down a set of, here, four individually movable arms 20 and 21. The two arms 20 are fixed, by set-screws 20a, on individual tubular rock-shafts 22, and the other or intermediate arms 21 are fixed, by set-screws 21a, on individual rock-shafts 23 journaled in the rock-shafts 22, each rock-shaft 22 and 23 protruding laterally from the terminal and having on its protruding end a handle 24; for holding each arm 20 and 21 at an elevation to which it is shifted its handle may be equipped with a pin 25 to enter one of the series of holes in a fixed segment 26. Each arm projects through the firing opening into the fire-box and at their free ends the arms are equipped with upstanding blades 20b, 21b; the blades 21b of the intermediate arms 21 diverge at one angle, and those 20b of the other arms 20 diverge at a greater angle, with respect to a vertical plane that is in medial relation to all the arms.

There is an eye 27 on the cover 13, a hook 28 on the door and a link 29 for separably connecting them, the purpose of which will hereinafter appear.

By the described mechanism the fireman can obtain and maintain proper distribution of fuel over the entire fuel-bed, including from back to front at each side, by opening some or all of the valves 18 more or less to bring into action and vary the force of the components of the entire blast possible and raising into the path of the resulting fuel stream such of the deflectors as his judgment dictates. In short, generally distributed and selective placement of the fuel on the fuel-bed is possible.

In the event that the fuel-forwarding part of the stoker becomes jammed or otherwise disabled the fireman can feed the mechanism by hand, to wit, by applying his foot to the pedal 10 which, with the opening of the door 8 by the means 9, will cause through link 29 the opening of the cover 13 (dotted position, Fig. 1) enabling him to shovel the coal into the thus-opened upper end of the terminal, which then becomes a receptacle or hopper having a forward outlet to the fuel-bed and means to discharge through such outlet the thus-delivered fuel.

If it is necessary for repairs or other purpose to clear the mentioned box surmounting terminal 1a from the firing opening such may be done by releasing the bolts 15 and swinging the box back on a pivoting bolt 29 or also by withdrawing such bolt and entirely removing the box, leaving the stoking to be done by hand in the usual way, in which case the door 8 (whose closing movement is according to the illustrated conditions limited to the position where it comes to rest on the box) would fall in closing to completely closing relation to the firing opening.

I claim:

1. In combination, a furnace having a firing opening, mechanical means to feed fuel through said opening including a conduit partially closing the opening and having a discharge outlet thereto and also a fuel-receiving opening, a movable closure for the firing opening, a movable

closure for the fuel-receiving opening, means coupling said closures for simultaneous opening and closing, and mechanical means for effecting movement of one such closure having man-controlled controlling means.

2. In combination, a furnace having a firing opening, mechanical means to feed fuel through said opening including a conduit partially closing the opening and having a discharge outlet thereto and also a fuel-receiving opening, a movable closure for the firing opening, a movable closure for the fuel-receiving opening, means disconnectively coupling said closures for simultaneous opening and closing, and mechanical means for effecting movement of one such closure having man-controlled controlling means.

3. In combination, a furnace having a firing opening, a fuel supplying means partially closing said opening and having a discharge outlet thereto and also a fuel-receiving opening, a movable closure for the firing opening, a movable closure for the fuel-receiving opening, means coupling said closures for simultaneous opening and closing, and mechanical means for effecting movement of one such closure having man-controlled controlling means.

4. In combination, a furnace having a firing opening, a fuel supplying means partially closing said opening and having a discharge outlet thereto and also a fuel-receiving opening, a movable closure for the firing opening, a movable closure for the fuel-receiving opening, means disconnectively coupling said closures for simultaneous opening and closing, and mechanical means for effecting movement of one such closure having man-controlled controlling means.

5. In combination, a furnace having a firing opening, a fuel receptacle communicating with the firing opening, a pressure fluid supply including a manifold forming a detachable upper portion of the rear wall of said receptacle, said manifold having a main chamber, and a plurality of secondary chambers, independent passages in the manifold connecting said main chamber with said secondary chambers whereby pressure fluid may be supplied to said secondary chambers, and a valve in each of said independent passages for independently regulating the supply of pressure fluid to a respective secondary chamber, said secondary chambers being provided with one or more jet outlets whereby pressure fluid is emitted in a sheet-like blast.

6. In combination, a furnace having a firing opening, a fuel receptacle provided with a removable housing portion having a discharge outlet to the lower portion of said opening and being mounted to swing away from the opening, and a mechanically operated firedoor normally closing the upper portion of said opening, the door being of size sufficient to cover the entire opening, said door automatically forming a closure for both said upper and lower portions of the firing opening when said housing is swung away therefrom.

7. The combination with a furnace having a firing opening, of a fuel receptacle communicating with said opening, said receptacle including at its upper end a removable housing hinged at its end remote from the furnace to swing away therefrom, a hinged cover for said housing mounted to swing toward the furnace, and a detachable manifold forming the rear wall of said housing.

8. The combination with a furnace having a firing opening, of a fuel receptacle having at its

upper end a housing portion communicating with said opening, said housing portion being hinged at its end remote from the furnace to swing away therefrom a removable top cover for said housing 5 and a detachable manifold forming the rear wall thereof.

9. In combination, a furnace having a firing opening, a conduit including a movable housing portion partially closing the opening and having a discharge outlet to the lower portion there-

of, a closure for the upper portion of said opening, said closure and said movable housing together constituting a cover for the firing opening, and means for moving said closure to uncover substantially the entire upper portion of said opening, the movable housing being hinged at its end remote from the furnace to swing away therefrom to substantially uncover the entire lower portion of said opening. 80
